CLAIM

I claim the ornamental design for a battery, as shown and described.

DESCRIPTION

FIG. 1 is a top, front perspective view of a battery, showing my new design;

FIG. 2 is a front perspective view from below of the claimed design of FIG. 1;

FIG. 3 is a front view of the claimed design of FIG. 1;

FIG. 4 is a rear view of the claimed design of FIG. 1;

FIG. 5 is a left side view of the claimed design of FIG. 1;

FIG. 6 is a right side view of the claimed design of FIG. 1;

FIG. 7 is a top view of the claimed design of FIG. 1;

FIG. 8 is a bottom view of the claimed design of FIG. 1; and,

FIG. 9 is a rear perspective view from below of the claimed design of FIG. 1.

The broken lines in the figures represent portions of the article which form no part of the claimed design.
